UNITED STATES PATENT OFFICE.

CHRISTINA MULLANEY, OF NEW YORK, N. Y.

EMERGENCY-COVERING FOR HATS.

1,096,184.

Specification of Letters Patent.

Patented May 12, 1914.

Application filed June 7, 1912. Serial No. 702,258.

To all whom it may concern:

Be it known that I, CHRISTINA MUL-
LANEY, a citizen of the United States, resid-
ing in the city of New York, borough of
5 Manhattan, county and State of New York,
have invented a certain new and useful
Emergency-Covering for Hats, of which the
following is a specification.

This invention is an emergency cover or
10 protector for hats, more particularly
women's hats, and it embodies an article
composed of waterproof material, prefer-
ably water proof paper, which, in the event
15 of a storm, may be readily applied to a hat
for the purpose of fully protecting it from
the elements.

A salient feature of the invention consists
in so constructing the covering or protector
20 that it entirely envelops the hat with its
edges folded over the brim and infolded in
the crown, so that it may be retained on the
hat by the customary hat pins used to secure
the hat in place.

Heretofore it has been proposed to use
25 hat coverings, but they have always been
composed of comparatively expensive ma-
terial, are more or less heavy and bulky, ex-
pensive to make, and, moreover, necessitate
30 the employment of drawstrings, elastic, or
other special attaching devices to secure
them in position on the hat. Furthermore,
the devices of the prior art are of a pre-
tentious, permanent construction, intended
35 for repeated reuse, whereas my new device
is intended, primarily, for a single use only,
and for emergency purposes, whereupon,
because of its trifling cost, it may be dis-
carded.

The present invention has numerous ad-
40 vantages over the protectors or coverings of
the prior art in that it is composed of in-
expensive material, may be very economi-
cally made, is not bulky or cumbersome, re-
quires no attaching devices to secure it in
45 place on the hat, is very light and slight,
and is particularly efficient for the purposes
intended.

In the accompanying drawings, I have
50 illustrated certain practical embodiments of
the invention, but the constructions shown
therein are to be understood as illustrative,
only, and not as defining the limits of the
invention.

Figure 1 shows a hat in elevation posi-
55 tioned on the head and with the protector, in

section, in normal position on the hat; Fig.
2 is a bottom view of the hat and protector;
Fig. 3 is a cross sectional view on line 3—3
of Fig. 2; Fig. 4 is a profile view of one form
of protector; Fig. 5 is a cross section on 60
line 5—5 of Fig. 4, the protector being prac-
tically collapsed; Fig. 6 is a profile view of
a modified form of protector; and Fig. 7
shows a bottom view of a hat with the pro-
tector of Fig. 6 applied thereto and having 65
one of its flaps folded into position within
the hat.

Referring to the drawings, particularly
Figs. 1 to 5, A designates a hat, B the pro-
tector, and C the hat pin for securing both 70
the hat and protector in position on the
head. The hat B has the usual brim b, and
band c, and it will be observed that the pro-
tector B completely incases or envelops the
hat, the lower portion thereof folding over 75
and beneath the brim b, with the edges d of
the protector folded within the crown of
the hat. When the hat pin C is inserted
through the hat, in the customary manner,
it is forced to pass through the in-folded, 80
edges d or lower portion of the protector,
thereby securely holding the protector in
position, and without necessitating the em-
ployment of any special attaching device.

The protector B is substantially conical in 85
shape, although it will be understood that
the precise shape of the protector, from a
broad aspect, is not material. In Figs. 5
and 7, however, I have shown the form of
protector B' which I have found best adapt- 90
ed for practical use. This construction is
substantially conical but with the apex, for
convenience in manufacture as well as ap-
pearance, removed therefrom, thereby pro-
viding a flat upper portion e. 95

The salient feature of novelty embodied
in protector B' consists in the provision of
the flaps f, preferably four in number,
whereby a very considerable portion of the
protector is dispensed with. This construc- 100
tion greatly facilitates the infolding of the
lower portion of the protector, the flaps f,
within the crown of the hat and, moreover,
leaves the infolded edges much less bulky
than in the form of protector illustrated in 105
Figs. 1 to 5. In Fig. 7 the hat is designated
A', the brim and band thereof being lettered
b' and c' respectively.

In view of the thin and fragile character
of the material which I prefer to employ 110

in the construction of the protector, I have found it advisable, in some instances to provide stays or reinforcing devices at those parts of the edges of the protector which are subjected to great strain. In Figs. 6 and 7 I have shown stays *g*, at the junction of the flaps *f* with the body of the protector. I prefer to insert these stays interiorly of the protector, so that when the protector is on the hat, the stays will be protected from the weather.

From the foregoing description, it will be observed that the protector is simple in construction, easily and economically manufactured, that it can be expeditiously applied to the hat, and that it is, necessarily, particularly efficient in operation and yet avoids numerous disadvantages adherent in prior constructions.

20 While the protector is more particularly adapted for use in rainy or stormy weather, yet it is of great utility as a protector to feathers and other delicate ornaments on a hat from wind and dust, such as are ordinarily encountered *e. g.* in automobiling.

The material from which the protector is made may, if desired, be semi-transparent, whereby the hat, showing therethrough, will produce a pleasing effect.

30 The device can be manufactured so cheaply as to enable it to be sold at a trifling cost, at news stands, hotels, railroad stations, etc., and its construction is such as to permit of its sale in the well-known vending machines.

35 While the invention has been particularly described with reference to its application to women's hats, and while this will naturally be its main field of use, it will be understood, of course, that the article, when slightly

modified in proportions and shape, is capable of use on men's hats.

Having thus fully described the invention, what I claim as new, and desire to secure by Letters Patent is:—

1. As a new article of manufacture, a 45 protector for hats, having a body portion for enveloping the hat, said body portion being of sufficient extent that its edges may be folded over the brim and infolded within the crown of the hat, whereby said pro- 50 tector may be secured in place.

2. As a new article of manufacture, a protector for hats composed of semi-transparent water proof paper for enveloping a hat and having free edges foldable within 55 the crown of the hat for securing said protector in place.

3. As a new article of manufacture, a protector for hats composed of water proof paper adapted to envelop a hat and pro- 60 vided with means entering the crown of the hat, whereby it may be secured to the hat by the customary hat pins employed to hold the hat on the head.

4. As a new article of manufacture, a pro- 65 tector for hats composed of water proof material, having a body portion for incasing a hat, said body portion being provided with extension flaps foldable within the crown of the hat, for securing said protector in place. 70

In testimony whereof I have signed my name to this specification in the presence of two subscribing witnesses.

CHRISTINA MULLANEY.
